UNITED STATES PATENT OFFICE.

ARCHIBALD COLBY, OF NEW YORK, N. Y.

DESIGN FOR A BADGE.

45,794.

Specification for Design.

Patented May 19, 1914.

Application filed November 25, 1913. Serial No. 803,057. Term of patent 3½ years.

To all whom it may concern:

Be it known that I, ARCHIBALD COLBY, a citizen of the United States, residing at New York city, in the county of New York and State of New York, have invented a new, original, and ornamental Design for Badges, of which the following is a specification, reference being had to the accompanying drawing, forming part thereof.

Figure 1, is an elevation view of a badge

formed in accordance with my new design, and Fig. 2, is a transverse sectional view.

I claim:

The ornamental design for a badge, as shown.

ARCHIBALD COLBY.

Witnesses:

GEO. A. BYRME,
M. C. LAUGHLIN.
